UNITED STATES PATENT OFFICE.

LOSSIE E. ANDERSON, OF CHICAGO, ILLINOIS, ASSIGNOR TO STANDARD OIL COMPANY, OF WHITING, INDIANA, AND CHICAGO, ILLINOIS, A CORPORATION OF INDIANA.

COMBINED SHIPPING CRATE AND TILTING CAN SUPPORT.

Application filed January 28, 1925. Serial No. 5,252.

This invention relates to improvements in combined shipping crate and tilting can support. By the use of my invention the ordinary rectangular-shaped oil can can be shipped in the device and protected against damage in transit. The device also serves as a tilting support for the can in use.

By the use of my invention, such a can of oil is protected by the crate in shipment; 10 and the crate also may be used for tiltably supporting the can to facilitate the pouring of the contents therefrom in use. The crate, as embodied in this invention, is of substantially the same size as the ordinary five- 15 gallon can crate now used for holding rectangular shaped oil cans.

Other features and advantages of my invention will appear more fully as I proceed with my specification.

20 In that form of device, embodying the features of my invention, shown in the accompanying drawings, Figure 1 is a view in side elevation of a crate, Fig. 2 is a view in rear elevation, partly in section, 25 of the same, Fig. 3 is a view of the same in side elevation, partly in section, showing the top of the crate removed and with a can or container in pouring position therein, and Fig. 4 is a top plan view of a 30 crate with a can therein, and with the top removed.

As shown in the drawings, the body of the crate is made up of a bottom member 5 on the opposite sides of which are secured 35 the side boards or members 6 which are preferably rectangular shaped boards, each forming one side of the crate. Each of these side members 6 is provided with a centrally arranged vertical slot 7 extending 40 downwardly from the upper edge to about the center of the member. In juxtaposition to each of these slots in front thereof at the upper end is provided a shorter parallel slot 8, say, about one-third of the 45 length of the slot 7. The portion of the side member between the slots is cut away to leave a low shoulder 9 therebetween, and the lower end of the slot 8 is rounded and lies a short distance below said shoulder.

50 At the base of the crate there are provided two vertical members or boards 10, one at the front and one at the back, which are secured to the side members 6 by any suitable means, for example, by nailing, and, 55 if desired, reinforcing strips 11 may be

secured to the lower edges of the side members 6 on the outside. The boards 10 have a height equal only to about one-fourth of the height of the crate; so that their upper edges will not offer an obstruction 60 to the tilting of the can in the crate, as will be explained more in detail hereinafter.

Within the crate there is removably mounted a cradle, made up of a horizontal square loop of strap iron 13, of a size and shape adapted to encircle a can to be carried in the crate such as, for example, the can 14. This encircling band 13 has its two ends outturned to form ears 15, and a bolt 16 passing through these ears serves 70 to clamp the encircling band securely to the can. A second U-shaped strap 17 passes around the bottom of the can, and has its ends securely fastened to the sides of the band 13, in any desired manner as by welding. At the points where the bottom member 17 of the cradle is secured to the encircling band 13, pins, pivots, or trunnions 18 are secured to the cradle in any suitable manner as, for example, by welding, 80 these pins being on opposite sides of the can and in a position so that they extend into the slots 7. The slots 7 are of such length as to accommodate the pins 18 with the can resting on the bottom of the crate. 85

In shipping, the can in the cradle is placed in the bottom of the crate, the pins 18 being in the slots 7, and is secured therein by placing on the crate a cover 19 having the depending cross members 20 which engage the front and back of the can at the upper edge and hold it firmly in place. The cover 19 may be secured by any suitable means such as by tying, nailing and the like.

90 It is believed that the operation of the device is clear. The can is shipped in the crate as it is shown in Figs. 1 and 2 with the cover on and is well protected. When it is desired to use the can, the cover 19 is removed, whereupon the can may be entirely lifted out of the crate, if desired, or it may be raised, until the pins 18 clear the shoulders 9, and moved slightly forward and lowered until these pins 18 rest in the bottom ends of the slots 18 which will form bearings for them permitting the can to be tilted as shown in Fig. 3 so that the contents may be discharged from the spout. When the pins 18 are thus resting 100 105 110

in the slots 8, the can is high enough so that it will clear the members 10 to permit the tilting.

While I have shown and described certain embodiments of my invention, it is to be understood that it is capable of many modifications. Changes, therefore, in the construction and arrangement may be made without departing from the spirit and scope 10 of the invention as disclosed in the appended claim, in which it is my intention to claim all novelty inherent in my invention as broadly as possible in view of the prior art.

15 What I claim as new, and desire to secure by Letters Patent, is:

Means for enclosing an oil can of commercial form and for serving the contents of such can while within such enclosing 20 means, comprising a crate of box-like form provided in its side walls with slots of

unequal length merging at their upper ends and cut away to form a shoulder between said slots, a clamping cradle embracing the can formed of an encircling member having tightening means at its free ends and equipped with pivot pins extending into the slots in the side walls of the crate, and a U-shaped member extending from said last referred to member and forming a rest 25 for the can, the can and cradle normally extending to the bottom of the crate and both so proportioned to the height of the crate as to permit of their being raised to cause the pivot pins of the cradle to ride 30 over the shoulder between the slots and to drop into the slot beyond the same whereby to permit the forward tilting of the can to serve oil therefrom.

Witness my hand this 24th day of January, A. D., 1925.

LOSSIE E. ANDERSON.
